UNITED STATES PATENT OFFICE.

FREDERICK H. PERRY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ROUNDING AND CHANNELING MACHINE.

1,272,708.

Specification of Letters Patent. Patented July 16, 1918.

Application filed September 25, 1916. Serial No. 122,004.

To all whom it may concern:

Be it known that I, FREDERICK H. PERRY, a citizen of the United States, residing at Beverly, in the county of Essex and State 5 of Massachusetts, have invented certain new and useful Improvements in Rounding and Channeling Machines; and I do hereby declare the following to be a full, clear, and exact description of the invention, such as 10 will enable other skilled in the art to which it appertains to make and use the same.

The present invention relates to channeling or rounding and channeling machines, and more particularly to machines adapted 15 to channel or round and channel the outer sole of a shoe after it has been temporarily secured in position, preparatory to permanently sewing or otherwise securing it to the shoe.

20 It has been customary in channeling the outsoles of shoes to cut the channel a uniform depth throughout and at a greater distance from the edge of the sole through the shank than about the forepart, the edge of 25 the sole being trimmed or chamfered off up to the edge of the channel flap in finishing the shoe after the outsole has been sewed thereto. In doing certain classes of work the trimming or chamfering of the edge of 30 the sole required along the shank is objectionable. For instance, in making shoes with thin edge shanks in which the sole edge is reduced in thickness by skiving the outsole outside the root or bottom of the channel through the shank, the subsequent trimming of the sole edge tends to nullify the 35 effect of the skiving.

It is the primary object of the present invention to so channel the sole that comparatively little cutting away or trimming of 40 the sole edge through the shank will be required in finishing the shoe. To this end one feature of the invention contemplates the provision of means for cutting a channel having its outer edge and the edge of 45 the channel flap a uniform distance from the sole edge and having its root or bottom a greater distance from the sole edge through the shank than around the forepart. 50 This manner of cutting the channel provides a wide channel flap in the shank which extends nearly to the edge of the sole so that little trimming is required in finishing the sole edge after the channel flap has been

laid. This is specially desirable in the case 55 of skived shanks, since the broad channel flap will be of sufficient width to properly cover the outseam, and the slight trimming required will not materially increase the thickness of the skived edge in the finished 60 shoe.

Any suitable means may be employed to cut the channel as above indicated, although it is preferred to utilize a channel knife of the usual construction so mounted that it 65 will cut a channel at a uniform distance from the sole margin, and an auxiliary knife for increasing the depth of the channel and width of the channel flap through the shank. In case a thin edge shank is to 70 be formed it is also preferred to utilize the auxiliary knife to skive the sole edge through the shank as well as to increase the depth of the channel and width of the channel flap. The skiving may, however, be 75 done as a separate and subsequent operation, if desired. The auxiliary knife may also be utilized not only to increase the depth of the channel through the shank but may also be utilized to skive the edge of the 80 sole about the forepart as well as through the shank.

The invention also includes certain further features of construction and combinations of parts hereinafter described and referred to in the claims, the advantages of which will be apparent to those skilled in the art from an inspection of the accompanying drawings and the following detailed description of the mechanism illus- 90 trated therein.

In the drawings, Figure 1 is a partial side elevation of a rounding and channeling machine showing the application of a preferred form of the present invention there- 95 to; Fig. 2 is an enlarged detail in side elevation of the channeling knives and their appurtenant parts, showing the auxiliary knife in active position; Fig. 3 is a front elevation of the parts shown in Fig. 2; Fig. 4 is a view similar to Fig. 2 (with 100 certain parts broken away to show internal construction), with the auxiliary knife in inactive position; Fig. 5 is a section taken on the line 5-5 of Fig. 2; Fig. 6 is a detail 105 representing the relative cutting actions of the two knives; and Fig. 7 is a view of a rough-rounded and channeled sole, illustrat-

ing the action of the knives of the present invention thereon.

The invention is shown in the drawings as embodied in a rounding and channeling machine which, in its main features, is substantially like the rounding and channeling machine shown and described in Letters Patent No. 1,030,606, dated January 25th, 1912. The machine is provided with a trimming knife 10, a channel-forming knife 12, a feed jaw 14, a crease guide 16, and a forepart guide 18 which is movable into and out of operative position by mechanism substantially as described in said patent. The channeling knife 12 differs in its mounting and mode of operation from the channeling knife shown and described in said patent, in that it does not move vertically to vary the distance of the channel from the margin of the sole. As is customary in the operation of rounding and channeling machines, the crease guide 16 engages the shoe during the cutting of the channel in the shank of the shoe, and upon the completion thereof, the forepart guide 18 is moved into operative position in engagement with the shoe. The operator throws the forepart guide 18 into operation by movement of a treadle rod 20. In addition to the channel knife 12 the machine is provided with a coöperative auxiliary knife 22 for increasing the depth of the channel through the shank. As shown, this knife is also constructed and operated to skive the edge of the sole through the shank. The auxiliary knife is normally in active position, as shown in Figs. 1 and 2, and is moved out of active position in passing from the shank to the forepart, and is again moved into active position in passing from the forepart to the shank.

When the operator manipulates the treadle, he thereby depresses the rod 20, which throws the forepart guide into operative position as described in said patent. This movement rocks a bell crank lever 24, pivoted at 26 in the frame of the machine. As the bell crank lever 24 is oscillated, a pin 28, fixed in the outer end of an arm 30 of the lever, is caused to travel in a slot 32 in a lever 34 which is pivoted at 36 in the machine frame. When the pin 28 reaches the inner end 38 of the slot 32, it swings the lever 34 and thereby rocks a bell crank lever 40 which is pivoted at 42, and is connected with the lever 34 by a link 44. The end of the link may be adjustably secured in a slot 46 in the lever 34 to regulate the movement of the bell crank lever 40 and thereby control, through the connections between the lever and the auxiliary knife 22, the movement imparted to the latter. The bell crank 40 is connected by a link 48 with a shaft 50 in such manner as to impart oscillations thereto. On the forward end of the shaft 50 is fixed an arm 52, pivoted on the outer

end of which is a link 54. The arm 52 and the link 54 are articulated by an eccentric connection 56 which provides means for adjusting the vertical position of the auxiliary knife with relation to the channeling knife. Fixed in the upper end of the link 54 is a pin 58, which engages a hole in a yoke 60 mounted for vertical movements on guideways 62 formed on a support or bend 63 which is formed or secured on the forward end of an oscillatory shaft 64. The construction and mode of operation of the shaft is substantially like the correspondingly situated shaft shown and described in said patent. The yoke carries the auxiliary knife 22 which is pivotally mounted thereon so that it may be given forward and backward as well as a vertical movement by the vertical movement of the yoke. Pivoted at 70 on the yoke 60 is a bifurcated oscillatory auxiliary knife support 72. Secured to the auxiliary knife support by a screw 74 is an adjustable knife carrier 76, the split upper end 78 of which is elongated to form a bearing clamp 80, in which is held the shank 82 of the auxiliary knife 22. A screw 84 clamps the knife in the carrier. The knife carrier 76 is provided with a curved groove 86 engaging a corresponding rib on the support, and is also provided with a curved slot 88 for the clamping screw 74. The center of the groove and rib is substantially at the point of intersection of the cutting edges of the knives 12 and 22, so that angular adjustment of the knife 22 will not disturb the proper coöperative relation between the knife edges. The means for advancing and retracting the auxiliary knife as it is moved vertically comprises a cam block 90 adjustably secured to the support 63 by a screw 92. A guide pin 93 holds the cam block from turning in case it is necessary to adjust it vertically. The cam block is provided with two cam grooves 94 situated on opposite sides of the block, which are adapted to be engaged by cam rolls 96 carried by the auxiliary knife support 72. The cam grooves 94 are of such shape that when the shaft 50 is oscillated to cause the link 54, and consequently the support 72 to rise, the auxiliary knife 22 is moved upwardly and backwardly into a position clear of the shoe sole, as shown in Fig. 4. The channel knife 12 is secured by means of a clamp 66 and screw 68 in a slot formed in a knife block 120 which is formed or secured on the support 63 and acts as a sole support adjacent to the point of operation of the knives. A supplemental sole support 98 is adjustably secured to the yoke 60 below the block 65.

During the sole channeling operation the channeling knife 12 is in constant engagement with the sole, and consequently cuts therein a channel, the outer edge of which is at a uniform distance from the margin of

the sole. The auxiliary knife is located a little to one side of the channeling knife, as shown in Fig. 3, and its cutting edge is disposed at such an angle that it intersects the 5 plane of the cutting edge of the channeling knife at its lower point. The cutting edge of the auxiliary knife extends below the lower point of the channeling knife and above the upper point of the channeling 10 knife. It is seen, therefore, that while the auxiliary knife is in active position, it will deepen the channel formed by the channeling knife, and simultaneously therewith the upper part of its cutting edge will bevel the 15 margin of the shank. The relation of the cutting edges of the two knives is indicated in Fig. 6.

During the operation through the shank the auxiliary knife remains in active position 20 as indicated in Figs. 1, 2 and 3, and acts to deepen the channel cut by the channel knife 12, and also to skive the edge of the sole beneath the channel flap, as indicated in Fig. 6. When the ball line is reached, the forepart 25 guide is moved into active position by depressing the treadle rod 20, and through the connections described the auxiliary knife 22 is raised and swung back out of active position, as indicated in Fig. 4. During the 30 operation around the forepart, or from the point indicated at 100 to the point indicated at 102, in Fig. 7, the auxiliary knife remains out of active position and a comparatively shallow channel is cut by the knife 12. 35 When the point 102 is reached, the forepart guide 20 through the connections described, moves the auxiliary knife forward and down into active position so that it acts to deepen the channel and skive the edge of the sole 40 during the remainder of the operation through the shank.

While it is preferred to employ the specific construction and arrangement of parts shown and described in embodying the invention in the rounding and channeling machine of the patent above referred to, it will be understood that this construction and arrangement is not essential to the broader features of the invention, and may be varied 45 or modified as found desirable or best suited to the construction of the machine in which it is to be embodied.

Having explained the nature and object of the invention, what is claimed is:

- 55 1. A channeling machine, having, in combination, means for cutting a channel in the face of a shoe sole and for increasing the depth of the channel during the channeling.
- 60 2. A channeling machine, having, in combination, means for cutting a channel having its outer edge a uniform distance from the sole edge and for varying the depth of cut and breadth of the channel flap during the channeling.
- 65 3. A rounding and channeling machine,

having, in combination, a trimming knife and means for cutting a channel having its outer edge a uniform distance from the trimmed edge of the sole and its bottom at a greater distance from the edge through the 70 shank than about the forepart.

4. A channeling machine, having, in combination, a channeling knife for cutting a channel a uniform distance from the edge of the sole, and an auxiliary knife movable into 75 and out of action during the channeling, and forming when in action a channel deepening extension of the channeling knife.

5. A channeling machine, having, in combination, a channeling knife for cutting a 80 channel a uniform distance from the edge of the sole, and an auxiliary knife movable during the channeling into and out of position to increase the depth of the channel.

6. A rounding and channeling machine, 85 having, in combination, a trimming knife, a channeling knife, a forepart guide, an auxiliary knife which when it is in operative position extends farther into the sole toward the medial line thereof than the channeling 90 knife, and connections between the forepart guide and the auxiliary knife for throwing the latter out of operation when the former is thrown into operation.

7. A rounding and channeling machine, 95 having, in combination, a trimming knife, a channeling knife arranged to cut a channel in the sole at a uniform distance from the margin thereof, and an auxiliary knife movable into and out of operative position 100 relatively to the channeling knife for cutting beyond it toward the medial line of the sole.

8. A rounding and channeling machine, 105 having, in combination, a trimming knife, a channeling knife for cutting a channel in the sole at a uniform distance from the margin thereof, and an auxiliary knife for deepening the channel cut by the fixed channeling knife in the shank of the sole. 110

9. A rounding and channeling machine, having, in combination, a trimming knife, a fixed channeling knife for cutting a channel in the sole at a uniform distance from the margin thereof, and an auxiliary knife 115 movable into and out of operative position for cutting a deeper channel in the shank than is cut in the forepart of the sole.

10. A rounding and channeling machine, 120 having, in combination, a trimming knife, a channeling knife, and an auxiliary knife for coöperating with the channeling knife to cut the channel in the shank of the sole, said auxiliary knife having provision for beveling the shank during the shank channeling operation.

11. A rounding and channeling machine, 125 having, in combination, a trimming knife, a channeling knife, and an auxiliary knife for coöperation with the channeling knife to 130

cut the channel in the shank and at the same time to bevel the shank.

12. A rounding and channeling machine, having, in combination, a trimming knife, 5 a channeling knife, and an auxiliary knife for deepening the channel in the shank and for beveling the shank.

13. A rounding and channeling machine, having, in combination, a trimming knife, a 10 channeling knife, and an auxiliary knife adjustable on an arc having its center at the intersection of the planes of the cutting edges of the channeling knife and the auxiliary knife.

14. A rounding and channeling machine, having, in combination, a trimming knife,

a channeling knife for cutting a channel at a uniform distance from the margin of the sole, and an auxiliary knife adjustable angularly with relation to the channeling 20 knife for cutting beyond the latter toward the medial line of the sole, and for cutting beyond the latter toward the margin of the sole.

15. A rounding and channeling machine, 25 having, in combination, a trimming knife, a channeling knife fixed on an oscillatory support, an auxiliary knife movably mounted on the support, and means for moving the auxiliary knife into and out of operative 30 position.

FREDERICK H. PERRY.
